DIVIDED PLATE

Charles L. Metzler, Palisades Park, N.J., and John D. Wark, Freeport, N.Y., assignors to Keyes Fibre Company, Portland, Maine, a corporation of Maine

Filed July 28, 1958, Ser. No. 51,941

Term of patent 14 years

(Cl. D44—15)

Fig. 1 is a top plan view of the divided plate of this new design; and

Fig. 2 is a cross-sectional view taken along the line 2—2 of Fig. 1.

The characteristic feature of our design resides in a divided plate having, in combination, a relatively narrow-flat rim with a rolled outer edge, a steep side wall extending downwardly from the rim to a narrow substantially flat shoulder and then terminating in a steeply curved bottom wall and a partitioning member joined at the ends thereof to the side wall of the plate and being of a height coextensive with that of the shoulder, substantially as shown.

We claim:

The ornamental design for a divided plate, as shown and described.
